BED BRACKET

Filed Nov. 13, 1948

UNITED STATES PATENT OFFICE

2,616,099

BED BRACKET

Joseph Silvio, Chicago, Ill.

Application November 13, 1948, Serial No. 59,843

3 Claims. (Cl. 5—207)

1

This invention relates to bed brackets and more particularly to bed spring and mattress supporting brackets.

In the past, various devices have been employed for positioning and supporting springs and mattresses within the framework of the bed. Most of these supporting devices have been used in connection with transverse slats or have had such slats constructed as an integral part thereof. Thus, for example Patent No. 1,883,693, is issued to this inventor in 1931, discloses a bed bracket for use in connection with such transverse slats. Obviously, the necessity for using transverse slats, although the number may be minimized by using the device taught by the aforementioned patent, is nevertheless undesirable. The necessity for using additional parts adds greatly to the expense and reduces the length of service of such devices.

It is, therefore, the primary object of this invention to provide a bed bracket which will overcome all of the aforementioned objections.

Another object is to provide a supporting device for bed springs which does not require the use of transverse slats therewith.

A further object is to afford a bed bracket which will insure positive and firm support for a bed spring and mattress within the framework of the bed.

Still another object is to provide a bed spring supporting device, the manufacture of which entails only simple bending operations.

Still a further object is to provide a bed bracket of simple, inexpensive construction, but which will nevertheless afford a safe, firm support for a mattress and spring.

With the foregoing and other objects in view which will appear as the description proceeds, the invention consists of certain novel features of construction, arrangement and a combination of parts hereinafter fully described, illustrated in the accompanying drawings, and particularly pointed out in the appended claims, it being understood that various changes in the form, proportion, size and minor details of the structure may be made without departing from the spirit or sacrificing any of the advantages of the invention.

For the purpose of facilitating an understanding of my invention, I have illustrated in the accompanying drawings a preferred embodiment thereof, from an inspection of which, when considered in connection with the following description, my invention, its mode of construction, assembly and operation, and many of its advan-

tages should be readily understood and appreciated.

Referring to the drawings in which the same characters of reference are employed to indicate corresponding or similar parts throughout the several figures of the drawings:

Fig. 1 is a perspective view of a conventional bed having the novel brackets attached thereto;

Fig. 2 is an enlarged fragmentary front elevational view of a portion of a bed, box spring and mattress, showing the bracket attached in operational supporting position to the bed frame element;

Fig. 3 is an enlarged fragmentary sectional view taken on line 3—3 of Figure 2 and viewed in the direction indicated; and

Fig. 4 is a still further enlarged fragmentary perspective view of a bed frame member with a bracket affixed thereto.

Referring now to the drawings, Figure 1 shows a conventional bed generally referred to by reference numeral 10, comprising a head-board 12, a foot-board 14 and longitudinal side frame elements 16 and 18 connecting the head-board 12 and foot-board 14.

Two pairs of novel bed brackets designated generally by reference numeral 20 are affixed to the inner sides of the longitudinal elements 16 and 18, one near each end, as shown in Figure 1 of the drawings.

The brackets 20 may be formed from a single strip of material 22 (preferably steel) by bending the strip at its mid-portion to afford an angle 24 having sides 26 and 28. The ends are then outwardly flanged to provide vertical mounting flanges 30 and 32. Each of these mounting flanges 30 and 32 may be apertured as at 34 so that ordinary wood screws 36 may be used to affix the brackets to the side frame elements 16 and 18.

When the brackets 20 are affixed to the side elements 16 and 18 in the positions shown in Figure 1, a bed spring S with a mattress M thereabove may be supported in a firm manner and level position by the brackets. Portions of the spring S will rest upon top edges 38 and 40 of the angle sides 26 and 28, and be supported thereby. This construction thus permits the bracket to support not only the mattress and spring, but also any normal load thereon.

It can be readily seen that this novel bracket not only affords a positive and firm support for a normally loaded bed spring and mattress, but also entirely eliminates the necessity for addi-

tional members such as transverse slats or similar supporting devices.

It is believed that my invention, its mode of construction and assembly, and many of its advantages should be readily understood from the foregoing without further description, and it should also be manifest that while a preferred embodiment of the invention has been shown and described for illustrative purposes, the structural details are nevertheless capable of wide variation within the purview of my invention as defined in the appended claims.

What I claim and desire to secure by Letters Patent of the United States is:

1. A supporting bracket comprising a strip of sheet metal bent acutely upon its vertical mid-axis to afford a structural angle of less than ninety degrees, end portions of the legs of said angle flanged outwardly to afford vertical and aligned faces adapted to be attached to the side frame members of a bed, portions of said face segments having holes formed therein and wood screws adapted to fit in said holes for affixing said bracket to the side frame members. 15

2. A supporting bracket comprising a strip of rigid strong material bent acutely upon its vertical mid-axis to afford a structural angle of less than ninety degrees, end portions of the legs of said angle flanged outwardly to afford vertical 20

5 and aligned faces adapted to be attached to the side frame members of a bed, portions of said face segments having holes formed therein and wood screws adapted to fit in said holes for affixing said bracket to the side frame members.

3. A supporting bracket comprising a strip of sheet metal bent acutely upon its vertical mid-axis to afford a structural angle of less than ninety degrees, end portions of the legs of said angle flanged outwardly to afford vertical and aligned faces adapted to be attached to the side frame members of a bed, and means for affixing said bracket to the side frame members.

JOSEPH SILVIO.
